UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

ROCK-DRILL.

1,057,732.

Specification of Letters Patent. Patented Apr. 1, 1913.

Application filed August 8, 1911. Serial No. 643,006.

To all whom it may concern:

Be it known that I, CHARLES C. HANSEN, a citizen of the United States, and resident of Easton, in the county of Northampton 5 and State of Pennsylvania, have invented a new and useful Improvement in Rock-Drills, of which the following is a specification.

This invention relates to rock drills and 10 is directed particularly to the construction of the drill bit and the means connecting it with the rock drill.

In the accompanying drawings, Figure 1 represents partly in side elevation and 15 partly in section so much of a rock drill, drill bit and connecting parts as will give a clear understanding of the several features of my invention. Fig. 2 is a transverse section taken in the plane of the line 20 A—A of Fig. 1, and Fig. 3 is a transverse section taken in the plane of the line B—B of Fig. 1.

The drill bit is denoted by 1, which bit is herein shown as removably secured in the 25 lower end of the drill steel 2 by providing the drill steel with a flaring socket 3 and the bit with a tapered portion 4 fitted to enter said socket 3. The upper end of the drill steel 2 is removably secured to a shank 5 in 30 the present instance by providing the lower end of the shank with a flaring socket 6 and the upper end of the drill steel with a tapered portion 7 fitted to enter said socket. This shank 5 is removably secured in the 35 chuck 8 of the work piston rod 9 of the rock drill. An axially arranged vertical passage 10 is formed in the drill bit 1, from which passage one or more holes 11 lead outwardly toward the cutting edge of the bit.

40 A check valve 12 is provided for this passage 10, which check valve is herein shown as located in the socket 3 between the upper end of the bit and the bottom of the socket. An axially arranged passage 13 45 leads through the drill steel 2, the bottom of which passage opens into the socket 3 and the top of which passage opens into the socket 6 in the shank 5. This shank 5 is provided with one or more laterally arranged holes 14 leading outwardly from the 50 socket 6. An apron 15 is interposed between a shoulder 16 on the shank 5 and the bottom of the chuck 8, which apron extends downwardly beyond the holes 14 in the chuck 55 for deflecting the water and material

pumped upwardly from the drill bit down along the steel. In the present instance, the depending portion of the apron 15 is provided with a flaring socket 17.

In operation; the bit with its steel is reciprocated in the usual manner by the rock drill and water is supplied to the hole being drilled in the proper quantity. As the drill is operated, the material cut by the drill bit is forced, together with the water, upwardly through the holes 11, passage 10 and passage 13 past the check valve 12. The valve 12 serves to prevent the return of the material through the bit. When the material finally reaches the top of the steel it is forced out through the holes 14 and deflected downward by the apron 15 along the sides of the steel.

The usual practice is to cover the hole being drilled by means of a piece of bagging 75 or burlap or other suitable material which will retain the coarser cutting material and permit the water to flow back again into the hole. In this manner very little water is needed for the drill operation as it is used 80 over and over. The use of means for deflecting the water and material downwardly not only prevents the loss of the water by its being expelled to a considerable distance 85 away from the steel but also serves to permit the operator to stand in close proximity to the drill.

It is evident that various changes might be resorted to in the form, construction and arrangement of the several parts without departing from the spirit and scope of my 90 invention; hence I do not wish to limit myself strictly to the structure herein set forth, but

What I claim is:—

1. A drill bit, and its steel having a passage for the discharge of the cut material, a check valve for said passage and an apron for directing the discharged material downwardly along the steel.

2. A drill bit, its steel and shank having a passage for the discharge of the cut material, a check valve for said passage and an apron surrounding the shank for directing the discharged material downwardly along 105 the steel.

3. A drill bit, its steel and shank having a passage for the discharge of the cut material, a check valve for said passage, the bit having the inlet holes and the shank the out- 110

let holes, and an apron surrounding the shank for directing the discharged material downwardly along the steel.

4. A drill bit and its steel having a passage for the discharge of the cut material and a check valve for said passage, said steel having a socket for receiving the bit, and an apron for directing the discharged material downwardly along the steel.

10 5. A drill bit, its steel and shank having a passage for the discharge of the cut material, a check valve for said passage, said steel having a socket for receiving the bit

and said shank having a socket for receiving the steel, and an apron surrounding the shank for directing the discharged material downwardly along the steel.

In testimony, that I claim the foregoing as my invention, I have signed my name in presence of two witnesses, this fourth day of 20 August 1911.

CHARLES C. HANSEN.
